To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of a vertical or perpendicular stripe formed of a vine of flowers and leaves and an ornamental line running spirally around a center vertical line, a vase-like ornament at the top of said stripe, with a 15 large group of roses and sprays of small flowers springing from the vase-like ornament, and an upright ornament below said stripe, with sprays of roses and smaller flowers and leaves diverging right and left from said upright ornament, as represented in the accompanying drawing. An upright ornamental

20 figure is arranged on each side of the large group of roses and are connected by an arch-shaped line extending over said group of roses, and ornamental scrolls diverging right and left from the base of said vertical line below the sprays of flowers and leaves, as shown in the drawing, and form part of the design. An ornamental band formed of interlaced lines of flowers and leaves and small ornaments 25 form the top and bottom of the design, as shown in the drawing.

25 What I claim is—
